DEVICE FOR PULLING STEEL PINS

Samuel A. Howerton, Edwardsville, Ill.

Application September 4, 1943, Serial No. 501,315

1 Claim. (Cl. 254—23)

The invention relates to devices intended primarily for pulling steel pins and the like from steel forms which are used in laying concrete. As is well known steel forms are used in the laying of concrete pavement and these forms are placed at the outer edge of the concrete for the purpose of holding the concrete in shape while it is being laid. Steel pins are driven through the forms and into the ground to hold the forms in place. The present device is designed primarily for the purpose of removing these steel pins so that the forms can be withdrawn from the concrete without the necessity for the operator stepping upon the concrete and without disturbing the concrete during the curing process. It will be obvious that while the invention is primarily intended for the pulling of steel pins from concrete forms it may also be used for other purposes, such as extracting nails, spikes, and the like.

The invention in its preferred embodiment includes a pair of lazy tongs provided with gripping jaws, the tongs being actuated by a lever hingedly supported upon an upright post or the like, although, if desired, other actuating means for the lazy tongs may be employed without departing from the spirit of the invention.

The invention will be more readily understood by reference to the accompanying drawing, in which is set forth an illustrative embodiment of the inventive thought.

In the drawing:

Fig. 1 is a perspective of the entire assembly including the upright supports, the operating lever and the gripping tongs;

Fig. 2 is a detail view showing the novel features of the gripping jaws.

Referring in detail to the drawing, A indicates an upright support of any suitable construction; B a lever pivotally mounted at any desired height on the upright support; and C denotes a pair of lazy tongs supported at one end of the lever and provided with gripping jaws for engaging a steel pin or the like.

As shown, the lazy tongs include a pair of steel strips 10 and 11 which may be approximately one and one-half inches wide and one-half inch thick, the strips being suitably pivoted to each other at 12. To form gripping jaws from the strips 10 and 11 the ends thereof are first heated sufficiently to permit working the same. The end portions 13 and 14 are then bent at right angles to the main portions of the strips, which bending operation, owing to the fact that the jaws are pivoted at 12, would necessarily cause the jaws to meet at an angle, thus interfering with their gripping action. 55

To avoid this difficulty the jaws are twisted or turned sufficiently so that the jaws will be in substantially the same plane when their meeting edges contact in the gripping position. To permit the jaws to engage a small pin or the like each of the jaws is notched to provide a central opening 15 to permit the shank of a pin or the like to pass therethrough, while at the same time permitting the edges of the jaws to contact beyond the margin of the opening. The jaws are suitably tapered adjacent the central opening so as to enable the jaws to contact the head of a pin even though only a very small portion thereof is exposed.

As shown in Fig. 1 one of the steel strips is preferably provided with an integral extension 17 which may be bent to provide a handle portion 18, by means of which the jaws may be caused to initially contact the pin and may be held in contact therewith until the jaws are caused to tightly grip the pin on operation of the lever B. The members 10 and 11 are pivotally connected at 19 and 20 to links 21 and 22 which complete the lazy tongs, which links are shown as provided with suitable openings 26, 26, through which is threaded an eye 23 of a bolt 24 which may be secured by means of a nut 25 through an opening in one end of the lever B. It will be understood, of course, that the ring 23 is closed after having been threaded through the openings 26, 26 in the links 21, 22.

The operation of the device will be apparent from the foregoing description. To grip the pin or the like the support A is set up adjacent such pin and the gripping jaws of the lazy tongs are lowered and brought into contact with the pin by means of the handle 15. The operating lever B is then actuated by pressing down on the handle, thus lifting the ring 23 and causing the pivot portions 19 and 20 of the lazy tongs to approach one another and at the same time causing the jaws 13 and 14 to tightly grip the pin, which pin is lifted as the operating lever B continues to be lowered. It will be noted that owing to the peculiar shape of the jaws 13 and 14 a firm grip upon the pin or the like is insured. Furthermore, owing to the presence of the handle 18 it is possible to properly locate the jaws so that they will not slip when the operating lever B is first actuated. Furthermore, the curvature of the ring portion 23, which is mounted through the links 21 and 22, insures a smooth but very firm gripping operation.

It will be apparent that the upright or standard A may be operated from a location adjacent

the concrete pavement in connection with which the forms are employed so that it is unnecessary for the operator to step upon the concrete and thereby disturb the concrete in the curing process.

While the invention has been particularly described in connection with the pulling of steel pins from steel forms it will be obvious that the apparatus may be used for other purposes without departing from the spirit of the invention.

I claim:

A device of the character described adapted to pull steel pins from forms used in laying concrete; comprising an upright support adapted to be positioned adjacent the pin to be pulled and having hinge receiving apertures at varying levels, a hinge member retained in one of said apertures, an operating lever hingedly mounted intermediate its ends on said upright by means of said hinge member, and pin pulling means of the lazy tongs type swingingly mounted adjacent one end of the lever, said pulling means including a pair of flat metal strips pivoted intermediate their ends and having gripping jaws at one end thereof each bent at substantially right

angles to the plane of the face of the strip from which it is formed and turned sufficiently to bring the bottom surfaces of the jaws into substantially the same plane in closed position, each of the jaws being similarly notched to provide a central opening to permit the shank of a pin to be engaged by the margins of the jaws adjacent said opening while permitting the edges of the jaws to substantially contact beyond the margins of the opening, the jaws being tapered adjacent the central opening so as to enable the jaws to firmly grip the end of a pin even though only a small portion of the pin is exposed, flexible supporting means for said pivoted strips comprising a pair of links loosely mounted at the end of said operating lever and pivoted to the ends of the metal strips opposite the gripping jaws, one of said pivoted strips having a rigid extension handle integral therewith and projecting beyond the point at which the strip is pivoted to its supporting link, said extension providing a handle for initially placing the jaws in contact with a pin to be pulled.

SAMUEL A. HOWERTON.
